John Robert Lend, 5247 W. North Ave., Chicago, Ill.

Filed Mar. 31, 1959, Ser. No. 55,271

Term of patent 14 years

(Cl. D9—2)

Figure 1 is a front elevational view of an instrument for cleaning hypodermic syringes and the like showing my new design;

Fig. 2 is a left side elevational view of Fig. 1;

Fig. 3 is a right side elevational view of Fig. 1, and

Fig. 4 is an enlarged top plan view of Fig. 1.

The dominant features of my design are represented in full lines in the drawing.

I claim:

The ornamental design for an instrument for cleaning hypodermic syringes and the like, substantially as shown and described.
